Intellectual Property Law Group(57) **CLAIM**

The ornamental design of a rapid exchange aspiration catheter, as shown and described.

DESCRIPTION

FIG. 1 is frontal perspective view of a design for a rapid exchange aspiration catheter;

FIG. 2 is a front elevation view thereof;

FIG. 3 is top plan view thereof;

FIG. 4 is a bottom plan view thereof; and,

FIG. 5 is another frontal perspective view of the embodiment of the design for a rapid exchange aspiration catheter shown in FIGS. 1-4, with a wire extending distally from a lumen in a lower portion of a wall of the rapid exchange aspiration catheter.

Broken lines are included in the drawings merely for the sake of illustrating an embodiment of an environment for the depicted embodiment of the design for a rapid exchange aspiration catheter, and form no part of the claimed design.
